DIPPER TOOTH

Arthur W. Daniels, Cedar Rapids, Iowa, and Joseph P. Murtaugh, Oak Park, Ill., assignors to Daniels-Murtaugh Company, Cedar Rapids, Iowa, a partnership

Application May 1, 1943, Serial No. 485,272

11 Claims. (Cl. 37—142)

The teeth of steam shovel dippers and other power driven excavating implements wear down with surprising rapidity in spite of the fact that they are made of tough manganese steel and are hardened by the pounding which they receive in service. The abrasive nature of the service to which they are subjected is so severe that replacement of the teeth is a substantial item in the cost of running an excavating implement.

For many years, it has been recognized that the difficulty arose not only from the amount of wear but the shape to which the teeth would wear. They have tended to wear rounded along the bottom front edge until very soon the teeth would act like runners of a sled and ride up on loose material instead of digging under it. It has been the practice to turn the teeth upside down fairly frequently in order to minimize this sled-runner effect.

According to the present invention, the shape of the point portion of the tooth has been so changed that the tooth wears sharp and will even stay sharp until it is worn back to the point where repointing becomes desirable. Without turning the teeth upside down, they will last considerably longer than previous teeth even when the latter were turned upside down, and during their entire life, they will be much more satisfactory than previous teeth. In fact, they may even be sharper almost to the end of their life than conventional teeth when they are new. In general, this result is accomplished by providing a shape which, although providing adequate strength, causes the tooth to wear flat instead of rounded on its bottom front edge.

At the same time, this new shape facilitates welding new points to the old tooth, saving both time and welding rod. This results from the fact that the channel formed in the bottom of the tooth in order to balance the wear and produce the flat bottom or self-sharpening wearing effect need not be welded and in fact forms a clear demarkation to show the welder where to weld and where not to weld.

In one form of the invention, the repointer and the base portion of the tooth are provided with interfitting V-type parts which accurately position the tooth for welding so that the teeth will be properly aligned in their digging function.

Additional objects and advantages of the invention will be apparent from the following description and from the drawings, in which:

Fig. 1 is a bottom view of the embodiment of the invention chosen for illustration of the form thereof at present preferred;

Fig. 2 is a side view of the structure shown in Fig. 1;

Fig. 3 is a fragmentary vertical sectional view taken approximately on the line 3—3 of Fig. 1;

5 Figs. 4, 5 and 6 are side views of modified forms of the replaceable points;

Fig. 7 is a bottom view of the point shown in Fig. 6, illustrating, however, optional features of shape for all of the illustrated points;

10 Figs. 8, 9, 10 and 11 are views illustrating a modified form of the invention, Figs. 8 and 9 being perspective views showing the repointed tooth respectively right side up and upside down, and Figs. 10 and 11, respectively, being side and bottom views of the repointer;

15 Figs. 12, 13, 14 and 15 are views of another form of the invention corresponding respectively to Figs. 8 to 11;

Fig. 16 is a perspective view showing drag-line 20 bucket equipped with teeth embodying the present invention, some of them having been repointed.

Several forms of the invention have been chosen for illustration and description, in compliance with Section 4888 of the Revised Statutes, but persons skilled in the art will readily perceive other means for accomplishing the same results, and the claims are therefore to be construed as broadly as possible, consistent with the 25 prior art.

This invention is illustrated in conjunction with a drag-line bucket 8 having a lip or base 9 for teeth 11. The invention could also be applied to a dipper or any other digging bucket. The 30 teeth may be removably secured as illustrated or they may be of any form. The particular form illustrated is one including a body portion 12 having its upper and lower faces converging toward the point, and a shank portion 13 provided with a key slot 14 through which a key 15 (Fig. 40) is adapted to pass to draw the tooth onto the base. The body portion includes wings 16, the inner faces 17 of which converge both toward the point and also laterally inwardly from the 45 sides. The base should be complementally shaped with clearances everywhere except at these converging surfaces. Thus, the tooth will be rigidly held by the base, vertical shifting being prevented by the V engagement seen in 50 a longitudinal vertical plane, and lateral shifting being prevented by the V engagement seen in a section perpendicular to the longitudinal axis of the tooth.

When the teeth of Figs. 1 to 8 are originally 55 sold, they may be a single casting or forging and

the body portion 12 will be extended to the point. The contour of the original tooth may be approximately as shown for the composite tooth in Figs. 1 and 2 or it may be quite different. Of course, the top and bottom converging faces of a new tooth would usually be smooth except insofar as special features of shape might require a departure from smoothness. After the point has been worn down on one side, the tooth may be turned over to wear the point down on the other side, although this is not usually necessary with the present invention.

When the tooth becomes worn to a point where it becomes unsatisfactory, a new point 21, called a repointer, is welded thereto. Usually it will be necessary to trim the body portion 12 with a torch ("burn" it) to the proper shape to permit the welding. The new tooth is preferably provided with a guiding ridge 20 to serve as a pattern. The preferred shape that the body portion 12 should have prior to welding is clearly shown in Fig. 2. The tooth is burned straight across between pattern ridges 20.

It will be observed that the point 21 does not fit snugly around the end of the body portion 12. In fact, each of them is of generally convex configuration. The purpose of this is to give access for welding. Usually the portion 22 will be filled in by welding first, thus providing an integral structure from the center line of the tooth to the top face of the tooth. This entire gap will be filled in solidly as shown. Next, the portion 23 shown in Fig. 3 will be welded in all the way across the tooth. The provision of the groove 24 in the underface of the tooth indicates to the welder the depth to which this weld 23 should be extended all the way across the tooth. Thereafter the portions 26 will be filled in by welding, thus providing a continuation of each rib 27 at the two sides of the groove 24. This method of welding provides a construction which has been found to have adequate strength for heavy duty excavating implements.

An even more important function of the groove 24 is in causing the tooth to wear sharp. It will be obvious that as the ribs 27 wear off, the tooth will be considerably thinner than if the channel 24 had been solid metal and the wear distributed all along this solid metal. From one standpoint, it might be said that the provision of channel 24 causes a balance in the wear of the tooth so that it wears thinner at the right speed to keep step with its wearing shorter. The tooth cannot be made thinner initially for it would not have adequate strength. The ribs 27 give adequate strength to the point although they wear down fast enough so that the tooth may be said to be self-sharpening. In short, the provision of the groove 24 extending to the tip of the tooth and of increasing width and depth rearwardly causes the vertical or upward diminution of the tooth to keep pace quite well with the rearward diminution, so that for a considerable period of wear the thickness of the front end of the tooth is not excessive or, in other words, the tooth stays reasonably sharp.

Having the tooth reduced in thickness to keep step with its shortening may not be quite the whole story since teeth in the past have had a tendency to wear rounded to the shape of a sled runner. The present tooth largely avoids this and it is believed that there are two factors which contribute toward it, one being the provision of the channel 24 and the ribs 27 and the other being the initial shaping of the tooth with a

bevel 30 which extends close to the bottom of the tooth. This causes nearly all of the loose material which would otherwise jam under the tooth and wear its underside rounded to be lifted upwardly and to pass over the tooth. In short, there is much less abrasive grit wedged between the bottom surface of the tip of the tooth and the more solid stone or other matter on which the tooth is being slid forwardly in the digging operation. It should be borne in mind that one common use of drag-line buckets for example is to strip coal or other material from a rock strata.

As seen in Fig. 1, the front end portion 29 of the ribs 27 is considerably wider than the rearward portion of the ribs 27. This has been found to increase both the strength and the wearing qualities of the forward portion of the point without disadvantage, since the tooth remains sharp as this portion of the tooth wears. It is desirable to shape the ribs so that they will wear just fast enough at each stage of wear to keep the tooth sharp.

Of course the exact shape which would be ideal from the standpoint of wear might vary somewhat with the nature of the digging operation. All of the shapes shown have been found to be fairly satisfactory. Those shown in Figs. 10, 11, 14 and 15 are now preferred, it being noted that the width of the groove 24 at the tip is approximately thirty percent of the width of the tooth at the tip. Further back, where the ribs 27 have greater depth to wear down, the groove is relatively wider and hence the ribs relatively narrower.

The groove 24 is valuable from the standpoint of efficient use of metal as well as from the standpoint of longer life. Even if the point became dull slightly faster with the groove 24 than without, there would still be the advantage of using fewer pounds of points for a given number of hours of operation than if the groove 24 were not provided.

The groove 24 has been shown as continued into the body portion of the tooth as at 31. This is not necessary but avoids having a projection which might strike rocks as the tooth is moved forwardly. When new teeth are provided with a groove 24 in casting, the groove will naturally be extended back for a gradual termination, as shown. However, when the tooth is not originally so formed, it will be optional whether or not the continuation groove 31 is burned into the body portion.

The shape of the tooth shown in Figs. 1 to 3 is at present the preferred shape. The radius of longitudinal curvature of the faces 32 is about eight to ten inches, although it is not at all objectionable for the upper face to be flat. The face 33 inside the groove has been illustrated as being flat at the front portion and then curved from there rearwardly. The various teeth are drawn approximately to scale. Of course, the size and shape of point will depend somewhat on the shape and size of the tooth for which it is designed, and in any event variations may be made from the dimensions and shape indicated.

Various other point shapes have been shown in Figs. 4 to 7, each of which will give good service, although at present the shape shown in Figs. 1 to 3, or a similar shape with parallel sides, is preferred, except that the self-aligning features of Figs. 8 to 11 are very desirable as an additional feature.

Fig. 7 shows a point which is wider at its tip 36 than at its rear end 37, and in which the ribs

27' have a flat taper 38 instead of a curved contour. Each of these features, the forwardly widened point and the flatly tapered rib, is optional with the different shapes of vertical cross section shown.

The repointer could of course be a little thicker at its rear end than has been shown so that it would correspond in thickness more to an extension of the body 12, indicated by the dotted lines 41. However, it is preferred to have the repointer slightly slimmer than the distance between the lines 41 so that the projecting ridge 42 will form a transverse guide for burning off the tooth to receive a new repointer. A new tooth is preferably of the same shape as the repointed tooth here shown so as to provide guide ridge 42 as well as the demarcation or ridge 20. Even if ridge 42 should be worn off slightly before a repointer was applied, the wear would produce a visible guide line.

In the form of tooth shown in Figs. 8 to 11, means is provided for correctly positioning the tooth repointer on its base during welding so that all of the teeth will be properly aligned. The proper alignment of the various teeth on a dipper is desirable partly to insure the self-sharpening wear of the teeth so that the dig line will be straight and horizontal. The latter reason is especially important where a rock strata is being stripped of coal since it is desirable to clean the coal from the rock as thoroughly as possible.

As is perhaps most clearly seen in Fig. 8, the tooth base 51 is provided on each side with a small recess 52, the top and bottom faces of which converge slightly rearwardly to form a V-shaped notch. The repointer 53 is provided with correspondingly shaped tongues 54. Because of their V-type of engagement with the recesses 52, the tongues 54 accurately align the repointer 53 with the base 51.

This not only positions the repointer accurately but also holds it while the welding process takes place. As in the case of the previous figures, the repointer may be welded to the base first along the bottom as at 56 and then along the top as at 58, or vice versa.

Usually the base 51 will be supplied with the recess 52 cast therein and the repointers 53 will, of course, always be formed by casting or otherwise with the tongues 54 thereon when they are to be used with the base 51. Of course if bases 51 having the recess 52 therein are not available, such recesses can be cut in old worn teeth with a cutting torch.

In Figs. 12 to 15, another form of repointer has been shown which has an advantage of simplified welding. The welding is simplified because although it extends over longer lines, there is no plane of cleavage and the welded bead may be much thinner.

In this instance, the repointer 61 is provided with rearwardly diverging legs 62 and 63. The leg 63 is provided with an opening 64 therethrough which serves the dual purpose of continuing the groove 24 and permitting access to the base 66 at its tip 67 to weld the repointer to the base along the tip of the base. The repointer will also be welded to the base along the lines 68, 69 and 70.

Of course the base 66 may be pre-formed to the desired shape but ordinarily an old tooth will probably be cut to this shape by the cutting torch and a raised line can be provided along the sides of the teeth as guide marks for this cutting if this type of repointer is to be used. Assuming that

the tooth base 66 is properly shaped it will be observed that the legs 62 and 63 will properly align the repointer and help hold it in position for welding.

5 The legs 62 and 63 do a large share of holding the repointer on the base and since there is no plane of cleavage, a minimum of welding will be sufficient. To a lesser extent, this same advantage is obtained in the structures of Figs. 8 to 11 10 since the tongues 54 interrupt the plane of cleavage which would be present without said tongues and to the extent of their strength reduce the amount of welding necessary.

From the foregoing it is seen that a tooth 15 point-shape is provided which makes the tooth self-sharpening in wear, and makes it sufficiently strong to withstand heavy duty. Furthermore tooth repointers (preferably of this shape) and methods of welding the same to the tooth base 20 have been provided which effect a tremendous saving in metal as compared to replacement of the teeth, which may be welded so easily that the cost of welding is much less than heretofore, and which in the preferred forms are self-aligning 25 prior to welding.

Fig. 16 shows another invention of applicants' 30 which may be described here very briefly since it is a divisible invention and will be the subject of another application. This refers to the shape 35 of the drag-line bucket 61. An important feature is that the foremost parts of the bucket are heavy hitch plates 62. The tips 63 of these hitch plates extend beyond the mounting facilities for hitch links 64 so as to serve as bumpers 40 when the bucket is dropped to the ground in dumped position (front end first). The hitch links 64 automatically fold in so that the chain connected to them will not be injured. The arch 45 66 rises vertically from a point forward of the teeth but rearward of the bumpers 63 so that it rarely strikes the ground. Furthermore, its center portion 67 is shaped to be approximately aligned with the direction of movement of the bucket in being dropped so that if it does strike it will strike fully edgewise and hence not be caved in. The balance of the bucket is exceptional.

We claim:

1. A tooth repointer for excavating implements 50 and the like, having upper and lower faces converging forwardly toward the tip and having a longitudinally extending groove of such dimensions that in normal use of the point the upward diminution of the point will keep pace with the rearward diminution sufficiently closely to maintain reasonable sharpness of the tooth as it wears rearwardly a substantial distance from the original tip, the downwardly exposed face within the groove being approximately parallel to the upper 55 face of the point for approximately at least one inch rearwardly from the tip of the point, and the groove widening rearwardly from the tip as it deepens, said repointer being convexly shaped on its rear end to facilitate welding it to a base tooth portion, and said groove being open at the rear end, thus demarking an area which need not be welded.

2. A tooth repointer for excavating implements 60 and the like, having upper and lower faces converging forwardly toward the tip and having a longitudinally extending groove of such dimensions that in normal use of the point the upward diminution of the point will keep pace with the rearward diminution sufficiently closely to maintain reasonable sharpness of the tooth as it wears 65 70 75

rearwardly a substantial distance from the original tip, said repointer being convexly shaped on its rear end to facilitate welding it to a base tooth portion, and said groove being open at the rear end, thus demarking an area which need not be welded.

3. A tooth for excavating implements and the like including opposed faces converging forwardly toward a tip to form a point, and having contour changes forming demarcations rearwardly of the point adapted to serve as guides for burning off the point along a path which will leave a convex surface on the front end of the remainder of the tooth appropriate for welding thereto a repointer having a convex rear face.

4. A tooth repointer for excavating implements and the like, having upper and lower faces converging forwardly toward the tip and having a longitudinally extending groove of such dimensions that in normal use of the point the upward diminution of the point will keep pace with the rearward diminution sufficiently closely to maintain reasonable sharpness of the tooth as it wears rearwardly a substantial distance from the original tip, and the tip of the tooth sloping downwardly and forwardly substantially to the bottom of the tooth whereby the tooth is self-sharpening as it wears, said repointer being convexly shaped on its rear end to facilitate welding it to a base tooth portion, and said groove being open at the rear end, thus demarking an area which need not be welded, and a tongue formed on the rear of the repointer with rearwardly converging faces to fit in a correspondingly shaped pocket of a member to which it is to be welded to properly align the repointer thereon.

5. A tooth repointer for excavating implements and the like, having upper and lower faces converging forwardly toward the tip and having a longitudinally extending groove of such dimensions that in normal use of the point the upward diminution of the point will keep pace with the rearward diminution sufficiently closely to maintain reasonable sharpness of the tooth as it wears rearwardly a substantial distance from the original tip, said repointer being convexly shaped on its rear end to facilitate welding it to a base tooth portion, and said groove being open at the rear end, thus demarking an area which need not be welded, and a tongue formed on the rear of the repointer with rearwardly converging faces to fit in a correspondingly shaped pocket of a member to which it is to be welded to properly align the repointer thereon.

6. A tooth repointer for the teeth of excavating implements and the like, comprising a block of a suitable metal for tooth points, shaped to form a tooth point, with opposed faces two of which converge toward the front end, and having rear face portions converging from opposed faces approximately to an intermediate point to permit access for welding between the said rear

faces and the generally convex end of the body portion of a tooth, and a tongue formed on the rear of the repointer with rearwardly converging faces to fit in a correspondingly shaped pocket of a member to which it is to be welded to properly align the repointer thereon.

7. A tooth repointer for excavating implements and the like, having upper and lower faces converging forwardly toward the tip and having at least one longitudinally extending groove in the lower face extending, at one longitudinal position, over half the width of the tooth and approximately half the thickness of the tooth, and including legs diverging rearwardly to fit over a correspondingly shaped tooth base portion for welding thereto, said groove forming an opening through one leg to give access to welding near the tip of the nose.

8. A tooth repointer for excavating implements and the like, having upper and lower faces converging forwardly toward the tip and having a longitudinally extending groove, said repointer being convexly shaped on its rear end to facilitate welding it to a base tooth portion, and said groove being open at the rear end, thus demarking an area which need not be welded.

9. A tooth for excavating implements and the like, including a base and a repointer welded thereto and having upper and lower faces converging forwardly toward the tip and having a longitudinally extending groove, said repointer and base being convexly shaped on their adjacent ends to facilitate welding them together, and said groove being open at the rear end of the repointer, thus demarking an area which need not be welded.

10. A tooth for excavating implements and the like including a base having a generally convex end, and a repointer comprising a block of a suitable metal for tooth points, shaped to form a tooth point, with opposed faces two of which converge toward the front end, and having rear face portions converging rearwardly from opposed faces approximately to an intermediate point to permit access for welding between the said rear faces and the generally convex end of the base, and a tongue formed on the rear of the repointer with rearwardly converging faces and fitting in a correspondingly shaped pocket in the base, said tooth being welded to the base in the alignment determined by said tongue and pocket.

11. A tooth base for excavating implements and the like having a convex end adapted to have a repointer welded thereto and having a small pocket in a forward portion of the end with rearwardly converging faces to fit a V-shaped tongue on the rear of the repointer which is to be welded to the base to properly align the repointer on the base.

ARTHUR W. DANIELS.
JOSEPH P. MURTAUGH.
